UNITED STATES PATENT OFFICE

CARL GUSTAF LEONARD SJÖLANDER, OF DALSBORG, SWEDEN

SECURITY LOCK

Application filed July 5, 1923, Serial No. 649,753, and in Sweden April 24, 1920.

This invention relates to security locks of which the head mechanism, placed on the inside of the door, is actuated by a spindle, passing through and secured in the door structure.

One object of my invention is to simplify the operations needed to open such locks, thereby using a key or gauge instead of a dial and needing no hole through the door structure.

Another object of my invention is to increase the convenience and utility of said locks so that they may be adapted for general use, where security is needed.

In general, I attain these objects by using a key receiver, secured to the outside of the door, and having a special mechanism, the motions of which are controlled by the key and transported to the inner lock mechanism by the spindle.

Another feature of my invention relates to such an arrangement of the acting parts of the key that said parts may be adjusted or combined in several ways and the lock tumblers be set according to the key combinations, the setting of new combinations to be used as often as desirable being made in a most convenient manner after the lock has been unlocked by use of the former combination.

In the accompanying drawings: Fig. 1 is an elevational view of the lock shown from the inside and with the lock case cover taken away. Fig. 2 a plane view of the lock with upper case wall partly broken away; Fig. 3 shows a tumbler; Fig. 4 shows tumbler separating washer; Fig. 5 shows a tumbler rack; Fig. 6 is a view of the key receiver seen from the inside and in elevation and with part of the body broken away; Fig. 7 is a vertical section through the lock, the door and the receiver, the lock section being taken on the line A—A of Fig. 1, the receiver section on the line B—B of Fig. 6; Fig. 8 is a vertical section of the receiver on the line c—c of Fig. 6; Fig. 9 and 10 views of the lock seen from the inside with the tumbler mechanism taken away; Figs. 11, 12 and 13 inside views of the tumbler arranging mechanism in several halts of its motions; Fig. 14 a section of the

spindle motion controlling catch; Figs. 15, 16 and 17 show the key for which the above mentioned receiver is designed; Figs. 18, 19 and 20 show another key; Figs. 21, 22, 23 and 24 show a receiver suitable for the last mentioned key; Fig. 22 is a section on the line D—D of Fig. 21 and Fig. 24 is a section on the line E—E of Fig. 23; Figs. 25 to 30 show other forms of keys and parts of receiver mechanisms suitable for such keys; Figs. 31 to 41 show a lock of simpler and cheaper construction than the lock illustrated by the above mentioned figures, where:

Fig. 31 is a vertical section through the lock, the door and the receiver; Fig. 32 is a vertical section of the key receiver shown from the outside and taken on the line F—F of Fig. 31. Fig. 33 is a plan view of the key. Fig. 34 is a vertical section of the lock on the line G—G of Fig. 31. Figs. 35 and 36 are respectively a plan view and section of the tumblers and a plan view and a section of a tumbler guide. Figs. 37, 38, 39, 40 and 41 are sections of the lock on the line H—H of Fig. 34, showing several positions in the motions of the lock mechanism.

In the lock case a frame 3 (Figs. 1, 2, 7 and 9) is located on projections, the lower part of the frame being provided with grooves for the racks 8 (Fig. 5). The racks are held in proper position by plates 9 or the like fixed to the frame by screws 10. The tumblers 12 (Fig. 3) each of which as usual is provided with a gate 13 in the untoothed part of the edge are rotatable on the shaft 14 in a fork-shaped lever 16, swingable on a shaft 17 in the frame 3. By turning a shaft 18 journalled in the frame 3 and provided with an eccentrically projecting pin 18^a gearing into a groove 16^b in one leg 16^b of the fork 16 the tumblers may be moved upwards and downwards and thus be brought into or out of engagement with the racks 8. The tumblers are separated from each other by means of washers 15, Fig. 4, each provided with a nose 15^a engaging a longitudinal groove in the shaft 14 in order to keep the washers in their positions, thus preventing the tumblers from disturbing one another in their proper motions. A cross bar 22 swingable on a shaft

55

95

100

20 in the frame 3 is arranged to engage the gates 13, these being adjusted in alignment under the cross bar.

In this case the key receiver consists of a member 26, Figs. 6 to 8, in which a cylinder 28 is arranged to turn and slide on a rod 29, the cylinder for this purpose being provided with a number of ring-shaped bevelled projections all alike, so that the cylinder may 10 act as a toothed rack in any angular position. The cylinder 28 may be moved axially in both directions by means of a hand knob 32, fastened to the spindle 33 passing through the door and joined to a toothed 15 segment engaging the cylinder. The left end of the cylinder is on its circumference provided with teeth 30 (Figs. 6, 8) the number of which equals the number of the tumblers and of the stops in the key. When the 20 cylinder is moved in one direction one tooth 30 passes a tooth 35 and when the cylinder is moved in the opposite direction the first mentioned tooth 30 passes a tooth 36, the teeth 35 and 36 being suitably fastened to the member 26 and bevelled so that they push the tooth 30 away and each turns the cylinder for a half step. The right end of the cylinder 28 is provided with wings 31 (Figs. 6, 7) arranged to cooperate with the stops in 25 the key to limit the rotary movement of the spindle. Thereby the degree of rotation of the spindle 33 is altered according to the depth of the stops in the key.

According to this embodiment the key may 30 be arranged for instance as shown in Figs. 15 to 17. The key consists of lamellæ, shown separately in Fig. 15, which are fastened in a holder 7 by means of a spring-actuated catch. Each lamellæ is provided with a step 40 or stop 34. Figs. 16 and 17 show the compounded key seen from two sides. The Figs. 6 and 7 show how the key is placed into the receiver. The steps or stops 34 in the key are arranged along or in a part of a circle, 45 in this case a third of the circle. As the number of stops in the key and teeth 30 on the cylinder 28 is twelve, in the case illustrated the space of the circle occupied by each single stop in the key is a 36th of the whole 50 circle. As the rotatory stop of the cylinder between two consecutive stoppings against the key is one 12th of the circle, and the space occupied by three consecutive stops in the key also is one 12th of the circle, one wing 55 31 will during one whole revolution of the cylinder 28 stop against the 1st, 4th, 7th and 10th stop in the key, another wing against the 2nd, 5th, 8th and 11th stop and the third wing against the 3rd, 6th, 9th and 12th stop. 60 For this purpose the wings 31 have to be arranged in suitable angles in relation to each other. In this case it is obvious that the number of wings 31 has to be three, as each one of them stops four times against the 65 key, and the number of key stops is twelve.

From the above explanations it will be understood that between the arrangement of the stops in the key and the number of wings on the cylinder there is in general such a relation that the size of that part of the circle, along which the stops in the key are arranged, 70 equals the whole circle divided by the number of wings on the cylinder.

In the lock case 1 is provided a moving mechanism of the same kind as that mounted in the receiver. Thus a cylinder 37 (Figs. 11 to 13) identical with the cylinder 28 and provided with bevelled teeth 40 is turnable and slidable on a shaft 38 in the lock case. The cylinder receives its reciprocal motion by means of a toothed segment 44 on the spindle 33, the teeth 40 on the cylinder and noses on plates 41 and 42, and the different parts are so arranged that the cylinder 37 and the cylinder 28 are moved synchronically. 80 During the reciprocating motion of the cylinder 37 the toothed racks 8 are moved by the wings 39 on the cylinder abutting against noses 11 of racks 8 and arranged in correspondence with the key stops. When the spindle is oscillated for as long strokes as the key stops will permit, the wings 39 on the cylinder 37 abut against the noses 11 and move the racks 8, the tumblers being thereby adjusted each in its turn so that the cross bar 22 may fall into the gates 13, whereby the lock bolt is freed. 90

It may be understood that the spacing of the teeth of the tumblers and the toothed racks must be such in relation to the thickness of the key lamellæ or to the distance between two adjacent stops 34 taken in the transverse direction of the key, that the sliding of the cylinder 28 for such a distance may cause the turning of a tumbler corresponding exactly to one or several whole teeth. 105

The inward and outward movement of the lock bar 24^a is caused by the following mechanism. 110

As shown in Figs. 1, 7, 9 and 10 toothed wheels 45, 46 and 47 gearing into each other are journalled next to that wall of the lock case which is placed against the door, the wheel 45 being fastened to the spindle 33, and the wheels 46 and 47 respectively being turnable on shafts 48 and 49 respectively. As usual in security locks a bolt fence 24 balanced by a weight 24^b is used for the inward and outward movement of the lock bolt 24^a. 115 Said fence is supported by an arbor 50 concentric to the toothed wheel 47 and fastened to the same, so that the arbor is movable with a certain friction in the boss of the fence. The fence is provided with a cam groove 23 (Figs. 9, 10) into which the inner end of the cross bar 22 gears in order to keep the fence in the position shown in Figs. 1 and 2 when the cross bar by means of the tumblers is held in raised position. An arm 51 on the boss of 125

the fence 24 is arranged to catch into a slot 52 in the wheel 46 on the side of the teeth, when the fence 24 is swung to the left. When the cross bar falls into the gates 13 the swinging movement of the fence is initiated by the cross bar as a result of said cross bar engaging the cam groove 23. By the turning of the knob 32 to the left the fence arm 51 is thereby caught by the wheel 46 and the movement of the fence is accomplished. When the knob afterwards is turned to the left the fence 24 is brought back to its starting position and raises the cross bar 22 out of the gates by means of the cross bar being caught by the cam grooves 23. The lock bolt is now again in locking position.

For the bringing back of the tumblers into their starting position a slide 54 is located in the wheel 46. Next to the toothed wheel 46 and in the same plane as the slide is arranged a lever 56, the free end of which extends in front of all the toothed racks 8 as shown in the Figs. 1, 2 and 7. When the lock should be locked, the key has to be taken out of the receiver and the cylinder 28 can then, by turning the knob 32 to the left, be moved until it stops against the opposite wall of the key hole, one of the tumblers 12 thereby being turned sufficiently to block the way for the cross bar 22. At the same time, a nose 55 on the slide 54 comes into contact with a pin 60, which forces the slide towards the lever 56 (Fig. 10). Then by turning the knob 32 to the right, the slide 54 catches the nose 57 and turns the lever over into the position shown by dash-dot lines in Fig. 10, thereby forcing all the racks 8 and tumblers respectively to their starting point. The cross-bar is now locked in raised position by all tumblers. Then the slide is forced into its initial position by means of the nose 57, the slide carrying on past the nose, the lever 56 having been stopped. Before the turning of the slide the nose 55 abuts against the pin 59 and the slide 54 thereby is forced out by the turning in opposite direction of the knob 32 and bringing the lever into initial position.

To maintain the synchronous movement of the cylinders 28 and 37 it is of importance that the direction of rotation of the spindle is not altered until the cylinders have made full strokes. For that reason the lock has to be provided with a device that prevents any false moves in that respect. This device may for instance be arranged in the following way.

A gear 62 engaging the wheel 45 (Figs. 11 to 14) on a shaft 63 in the lock case is connected to an arbor 64 which supports a catch 65, provided with teeth 66, 67. This catch is turnable with certain friction on the arbor 64 and is intended to cooperate with a toothed segment 68 which is fastened to the wheel 45 or to the spindle. The rotating movement of the catch is limited by the pins 60, 61, so ar-

ranged that the tooth 66 in the two end positions allows the teeth of the toothed segment 68 to pass in the direction away from the tooth. When a tooth 40 on the cylinder 37 during the movement of the spindle in the direction of the arrow in Fig. 11 comes into contact with the bevelled end of the plate, a tooth 30 on the cylinder 28 (Fig. 6) just touches the bevelled tooth 36. By the further movement in the same direction the two cylinders will turn simultaneously for a half step. If now the operator by any chance would try to reverse the direction of rotation of the spindle 33 whilst the operation is being performed, the catch 65 being already brought into the shown position will snap against a tooth on the toothed segment 68. (Fig. 12). First when the parts have attained the positions shown in Fig. 13, the spindle is able to be turned in the opposite direction. When this happens each of the teeth 42 and 35 comes into contact with a tooth 40 and a tooth 30 respectively on the cylinders 37 and 28 respectively, the catch having been brought into the position shown in Fig. 10, whereafter the cylinders by a continued turning of the spindle are moved for the remaining half step. Hereby the catch 65 also prevents in the described manner the turning backwards of the spindle before said movement is accomplished.

To open the lock the operator has first to turn the knob to the right in order to bring the racks 8 into their starting positions. Thereafter he has to insert the key and oscillate the knob 32 until the lock bolt is drawn in.

The setting of the lock for a new combination of the key is made in the following manner:

After the lock bolt has been forced out, the key having been left in the receiver, the operator turns the eccentric 18 to the left (Figs. 1, 2) by means of an appropriate tool until it stops, whereby the tumblers 8 are raised until the cross bar comes into contact with the bottom of the gates 13. Then the key is removed and its lamellæ are adjusted for a new combination, the knob is turned to the left and to the right until it stops in order to bring the racks which are now free from the tumblers into their initial position. Thereafter the key is inserted again and the knob is oscillated in full strokes at least as many times as there are tumblers. Then the eccentric 18 is turned back whereby the tumblers again engage the racks. Now the lock is set for the new combination.

As may be understood the key may be altered in many ways without its being necessary to alter the lock in point of principle. Thus, the Figs. 18 to 20 show a lamelled key of a slightly altered form. As may be seen in Fig. 18 each of the lamellæ is provided with a round opening 69 at the periphery of which the stop 34 is placed. Each stop is so placed

that if one supposes that the compounded key were divided into as many sectors as the number of lamellæ in the key one stop will correspond to each sector (Fig. 19). The lamellæ are removably fastened in a holder shown in Figs. 19 and 20.

A receiver suitable for keys lamelled or not lamelled is shown in Figs. 21 to 24. The rotatable toothed cylinder 71 which is movable axially and corresponds to the cylinder 28 described above is directly located in the receiver body 26. The projecting end 73 of the cylinder 71 is small enough to move freely past the steps 34 in the key and is provided with a projection 74 arranged to come into contact with each of the stops 34. The other features of the receiver are approximately identical with those of the receiver described above.

In the Figs. 25, 27 and 29 are shown keys formed in other ways and in the Figs. 26, 28 and 30 the cylinder 71 arranged in correspondence with each of said keys. The Fig. 25 shows three lamellæ of a key by which each lamella is provided with holes arranged around a circle for the small end 76 of the cylinder 71. The number of the holes is one less than the number of lamellæ but the spacings between the holes are counted according to the whole number of lamellæ. In each lamella is one spacing 72 left free of hole, this free spacing being at different places in all lamellæ. Thus, between two holes in each lamella there is an unbroken surface which in the respect of situation and function corresponds to the step 34 in the keys described above. The small end 76 of the cylinder 71 is intended to come into contact with each of said unbroken surfaces in the compounded key in a way corresponding to that in which the projection 74 of the cylinder 71 comes into contact with the stop 34.

The key according to the Fig. 27 consists of a disc provided with holes 77 arranged on a circle, there being one hole for each tumbler. Said holes are countersunk to different depths, so that the small end 78 of the cylinder being conical and corresponding with the holes will penetrate to different depths in the key and the cylinder thereby be moved axially for different lengths between each step of rotation in the same manner as by using the keys described above.

The key shown in Fig. 29 differs from the key shown in Figs. 18 to 20 only in that respect that it is made in one piece and formed to a cylinder which is coaxial to the opening. The projection 74 of the cylinder 71 here operates with the steps or stops 79 corresponding to the stops 34 of the key mentioned before. The two keys lastly described not having adjustable stops must be substituted if the lock is to be set for a new combination.

The lock shown in Figs. 31 to 41 is of a

simpler construction showing how the lock according to the idea of the invention may be arranged for a key with fixed stops. Although the lock in this form does not fulfil the same standard of safety as the embodiment described above it has the advantage of being able to be manufactured for a comparatively low price.

As may be seen in the figures the spindle 81 passing through the door structure 82 is rotatable and movable inwards and outwards for a determined distance. 85 indicates the wings on the spindle cooperating with the stops of the key 86. In Figs. 31 and 32 said key is shown inserted in the receiver here consisting of a sleeve 87, in the wall of which is made a transverse opening for the key. The form of said key may be seen in Fig. 33. The stops of the key and the wings on the spindle are arranged on the same principle as by the embodiment shown in Figs. 1 to 17 with that difference in respect of the key that the stops are made in one piece.

The spindle 81 is here intended to be substituted for the cylinders 28 and 37 or corresponding members, and for that reason it is turned stepwise at the same time as it is moved inwards and outwards by means of the knob 83. In order to cause the turning movement of the spindle the lock case is provided with the following device. On the inner end of the spindle is fastened a disc 88 provided with a number of holes 89 arranged at the same distance from each other and from the centre. Further two pins 117 and 118 are fastened in the lock case, one on each side of the disc and arranged to centre each of the holes 89. As the spindle is pushed inwards the pin 118 centers one hole 89, the pin being so located that the disc and the spindle respectively are turned just for a half step. Hereafter the disc slides on the pin 118, whereby the spindle gets the necessary guiding. When the spindle is pulled backwards the pin 117 centres one hole 89 at the same moment as the disc leaves the pin 118, and the pin 117 is so located as to thereby turn the disc and the spindle for remaining half step. Thus, the spindle will be turned one whole step during each complete reciprocating movement inwards and outwards.

The sliding tumblers 91 (Fig. 35) are here arranged to be actuated directly by the spindle. They are so located between guide lamellæ 93 (Figs. 34, 36) fixed to the lock case that they may be moved longitudinally. Each tumbler is sufficiently guided by means of a groove 126 in it and a corresponding longitudinal cam 125 on the guide lamella. The spindle adjusts the tumblers by means of noses 90 on the disc 88 cooperating with noses 92, one on each tumbler. Said noses 90 correspond to and act in the same manner as the wings 39 on the cylinder 37.

The mechanism of movement for the lock

bolt is constructed in the following manner.

A toothed segment 95 turnable in the lock case on a pin 96 gears into a toothed wheel 99, which is turnable on a stationary pin 100 and joined to an arbor 101. On said arbor is a friction arbor 102 from which extends the bolt fence 103 which in known manner moves the lock bolt 104 forwards and backwards. Said fence as usual gears into a gate 105 in the lock bolt. The arbor 102 is further provided with a longitudinal cam 106, in the wall of which are located the tumblers and one part 107 of the toothed segment 95, said part 107 being situated over the teeth 15 of the segment 95. The toothed segment 95 is provided with a gate 120 in the part 107 arranged to correspond to the gates 119 in the tumblers. The mechanism is coupled to the spindle by means of an arm 97 of the segment 95 being provided with a slotted bolt 98, which is turnable in the arm and embraces the disc 88 whereby the segment receives an oscillating movement, when the spindle is reciprocated.

25 The mode of operation of the mechanism is described below and is shown in Figs. 38 to 41. In order to unlock, the spindle 81 is moved in and out by the aid of the knob 83 (Fig. 31) after the insertion of the key, until 30 the lock bolt is withdrawn.

During its reciprocating movements the spindle will move one tumbler more and another tumbler less corresponding to the depth of the key stop in question. Each stop 35 is in such relation to the gate 119 in the corresponding tumbler that said tumbler is moved just as much as is needed for the gate to come opposite the cam 106. When all the tumblers are adjusted in this manner and the 40 gate 120 in the oscillating segment 95 next time comes opposite the cam the way is free for said cam, and the friction arbor 102 is thereby turned by the arbor 101 moving at this time in the direction of the arrow in Fig. 45 29, so that the cam 106 engages the gate 120, whereby the lock bolt is moved backwards (Fig. 39). The cam hereby brings the tumblers with it. When the spindle next time is moved inwards the lock bolt is again moved 50 into locking position and the tumblers are moved back by the cam 106 into disengaging position. When the key is taken out the lock bolt is blocked by the spindle being moved 55 inwards once again, thereby moving to the bottom and bringing one of the tumblers into the way of the cam 106, see Fig. 40.

The device for moving back the tumblers consists of a lever 109 (Figs. 37 to 41) which 60 is swingable on a pin 108 and provided with a projection 110 on the boss acting as a support for another lever 113. Each of said levers is actuated by a spring 114 or 115 respectively (Fig. 34), so that they when resting hold the positions shown in Figs. 37 and

39, the rear end of the lever 113 thereby resting against the boss of the lever 109.

When the tumblers are to be moved back into starting position the key is taken out and the spindle is moved inwards as far as possible. Hereby a nose 121 on the arm 97 of the toothed segment shoves away the lever 113 and finally passes said lever 113 (Fig. 40). When the toothed segment 95 is moved backwards both levers are brought with it whereby the lever 109, the width of the free end of which corresponds to the distance between the two outermost tumblers, moves the tumblers into their starting position (Fig. 41). When the toothed segment 95 next time is brought 75 backwards the nose 121 releases the lever 113 and the position of the parts is again that shown in Fig. 37.

The embodiments described above show how the lock may be altered in different ways within the scope of the invention. It is therefore a matter of course that such modifications of the lock which consist of a combination of certain details of the described embodiments also fall within the scope of the invention. 80

Having now described my invention, what I claim as new and desire to secure by Letters Patent is:

1. In combination, a lock operable by a key and including a spindle adapted to be located in a door structure, a key receiver located on the outside of the door, said receiver having a cylinder movable therein, a wing on said cylinder adapted to stop against the steps of a key, teeth on said cylinder, fixed members adapted to co-operate with said teeth to rotate the cylinder step by step and guide it during axial movement, means connecting the spindle and cylinder for moving the latter axially, a lock mechanism located on the inside of the door structure and including a toothed cylinder operable by said spindle, wings on the second cylinder, racks operable by the second cylinder, and toothed tumblers co-operating with said racks, said tumblers being brought 95 into their unlocking position during oscillation of the spindle, the first mentioned cylinder being adapted to be stopped against the 100 steps of a key. 105

2. In a lock, a spindle adapted to be located in a door structure, toothed tumblers, racks co-operating with said toothed tumblers, a frame supporting the tumblers, means for moving the frame with the tumblers from and towards the racks whereby the racks may be free from the tumblers while the racks are being set for new combinations and the tumblers may again engage the racks after the new combination is set. 110

3. In a lock, a spindle adapted to be located in a door structure, a movable frame, tumblers located in said movable frame, a lock bolt, a fence for moving the lock bolt, a movable cross bar adapted to enter the tumbler gates and cooperate with the fence whereby to con- 115 120 125 130

trol the motions of the fence, said bar being adapted to be stopped when the tumblers are disengaged from the racks whereby to prevent the fence from moving while the racks are set for new combinations.

5 4. In a lock, a spindle, tumblers, two toothed cylinders, one cylinder adapted to act on the lock key and the other on the tumblers, means for rotating the cylinders step by step, 10 said cylinders being movable axially by the spindle, a toothed wheel actuated by the spindle, a friction-actuated catch, co-operating with the teeth of said wheel to control the motions of the spindle and to maintain synchronization of rotation of the two cylinders by compelling the operator to make full oscillating strokes with the spindle.

15 5. In a lock, a spindle, a wheel operable by the spindle, a slide located in said wheel, fixed pins, a lever, tumblers, said slide being put into working positions by said pins and adapted when the key is withdrawn and the spindle oscillated, to catch and swing said lever whereby to force the tumblers back to 20 their starting point in the unlocking position.

25 6. In a lock, a spindle adapted to be located in the door structure a lock mechanism located at the inside of the door, a key receiver located at the outside of the door, means for cooperation of the lock mechanism with a key for unlocking the lock when the key has been inserted in the key receiver, said means being operable by said spindle, and means for setting the lock mechanism for new combinations whereby to render it operable by new 30 keys.

In witness whereof, I have hereunto signed my name.

CARL GUSTAF LEONARD SJÖLANDER.
